EASY OPENING CONTAINER

Greeley Baker, Chicago, Ill., assignor to Continental Can Company, Inc., New York, N. Y., a corporation of New York

Application June 12, 1933, Serial No. 675,501

1 Claim. (Cl. 220—53)

The invention relates to new and useful improvements in an easy open container.

An object is to provide a sealed container having a cover which is hermetically joined to the body portion by breakable bonding material in which the body portion of the container and cover are shaped so as to provide a pouring spout when the cover is removed.

A further object of the invention is to provide a container of the above type described having a strengthening bead extending all the way around the periphery of the upper end thereof, whereby when the cover is removed a smooth and unbroken edge is provided.

15 These and other objects will be hereinafter more fully disclosed.

Referring to the drawing:

Figure 1 is a perspective view of the sealed container.

20 Figure 2 is a top plan view of the same.

Figure 3 is a sectional view taken along the line 3—3 of Figure 2.

The invention relates broadly to a metal container, the lower end of which is circular and the upper portion of which is tapered and shaped to provide a pouring spout for the container. A bottom closure is double seamed to the lower circular portion of the container in the well known manner, and a cover cut to follow the conformation of the spout is joined to the other end by a soft breakable solder bond. The container body is provided with an outwardly rolled bead extending all the way around the periphery of the upper end thereof to which the cover is soldered. This bead not only strengthens the mouth of the container in the region of the pouring lip, but also presents a smooth and unbroken surface to the hand after the soldered attached cover has been removed. The cover is provided with an extending tongue to which a key of any well known type may be engaged for rupturing the solder bond and removing the cover.

Referring more in detail to the drawing, the container illustrating the invention consists of a body portion 1 to the bottom end of which is attached a closure 2. Said closure is secured to the body portion by a double seam indicated at 3. The body portion is preferably circular at the lower end and tapers slightly toward its upper end. It is also shaped so as to provide a pouring spout at the upper end thereof which is indicated at 4 in the drawing. The body portion is shaped so that the pouring spout gradually vanishes into the body portion midway of the height

of the container. The body portion at its upper end is rolled outwardly into a hollow bead 5. This hollow bead extends all the way around the periphery of the upper end of the can body including the pouring spout. One purpose of this hollow bead is to strengthen the upper end and maintain its shape, thus maintaining the shape of the spout. Another purpose of this bead is to provide a smooth upper edge for the can body. The can body is also provided with a bead 6 which is substantially parallel with the bead 5 and spaced therefrom. This bead 6 extends all the way around the can body and spout and strengthens the can body and aids in maintaining the shape of the spout.

The container is closed by a cover 7 which is shaped to conform to the upper end of the container and the spout. This cover 7 is dimensioned so that when placed on the hollow bead 5, extending around the peripheral edge of the container body, it will overlie the bead as indicated at 8. The cover is placed on the container body and held pressed thereagainst and a solder bond 9 is placed between the hollow bead and the overlying edge portion 8 of the cover. This solder bond is preferably made of soft solder which produces a hermetically tight joint to which is readily ruptured for the opening of the container. The cover 7 is provided with an extension 10 on the portion thereof overlying the spout, and this extension 10 serves as a tongue to receive a key indicated in broken lines at 11. The key is slipped onto the tongue and then the key is turned so as to roll the cover onto the key as indicated in dotted lines at 12 in Figure 3. In this way the solder bond is ruptured and the cover removed.

The extension 10 is preferably turned down so as to extend substantially along the wall of the container for the purpose of protecting the extension. The end 7 is preferably attached to the container body by the manufacturer of the container. The container is then filled by the packer after which the bottom end 2 is attached thereto by double seaming.

When it is desired to open the container the key is placed on the extension or tongue 10 and the cover is rolled onto the key, rupturing the solder bond and thus completely removing the cover from the container. The container described above is particularly adapted for a dispensing oil at oil servicing stations for automobiles. Oil is hermetically sealed in the containers by the oil distributor and is marketed in these containers. The key is preferably at-

tached to the cover by solder bonding, and is used for removing the cover after which the oil can be poured from the container through the pouring spout into the receiving pipe of the 5 crank case. This container, after it is emptied, may be readily used as a measuring container, and the strengthening bead may be placed so as to indicate the predetermined measured amount of liquid.

10 It will be evident that minor changes may be made in the structure as illustrated without departing from the spirit of the invention as set forth in the appended claim.

Having thus described the invention, what I 15 claim as new and desire to secure by Letters Patent, is:—

A metal container including a body portion, the lower end of which is circular and the upper part of which is shaped to form a circular por-

tion leading into a projecting spout gradually vanishing into said circular body portion, said container body having an outwardly rolled bead at its upper end extending all the way around the periphery thereof, including the spout, said body portion having a strengthening bead parallel with the bead at the end and extending all the way around said body portion including the spout, a bottom seamed to said body portion, and a cover resting on and overlying said bead 10 at the upper end of the body portion of the container and secured to said body portion by a breakable solder bond, said cover at the portion thereof overlying the spout having an extension extending downwardly parallel with the wall of 15 the container and adapted to receive the key on which the cover may be rolled for breaking the solder bond.

GREELEY BAKER.
